UNITED STATES PATENT OFFICE.

LYNN W. MACOMBER, OF BATTLE CREEK, MICHIGAN, ASSIGNOR TO ALSTEEL
MANUFACTURING COMPANY, OF BATTLE CREEK, MICHIGAN, A CORPORA-
TION OF MICHIGAN.

BALING-PRESS.

1,142,188.

Specification of Letters Patent.

Patented June 8, 1915.

Application filed June 19, 1914. Serial No. 846,074.

To all whom it may concern:

Be it known that I, LYNN W. MACOMBER, a citizen of the United States, residing at Battle Creek, in the county of Calhoun and 5 State of Michigan, have invented certain new and useful Improvements in Baling-Presses; and I hereby declare that the following is a full, clear, and exact description thereof, reference being had to the accompanying drawings, which form part of 10 this specification.

This invention relates to balers, or machines for compressing light or bulky material such as waste papers, rags, etc., and 15 its object is to provide an efficient, easily operated, portable baler, which will be capable of withstanding rough usage, and in which all parts may be made of metal.

The invention resides in the novel construction and arrangement of parts of the baler, as hereinafter more particularly described with reference to the accompanying drawings and set forth in the claims, it being understood however that the invention 20 is not restricted to the specific proportions and construction of parts illustrated in the drawings, which however illustrate a practical baler embodying the invention.

In said drawings:—Figure 1 is a perspective view of a baler with the follower or presser head raised, and the upper door open. Fig. 2 is an enlarged vertical section through the baler, showing the operative parts, part of the baler body being broken 25 away. Fig. 3 is an enlarged top plan view of the baler. Fig. 4 is a vertical section on line 4—4, Fig. 2. Figs. 5 and 6 are detail sectional views.

The baler comprises a body or baling chamber which is preferably arranged vertically and comprises opposite side walls 1^b and rear wall 1^a which are preferably stamped out of a piece of sheet steel and are rigidly secured to the metallic base 45 frame 1. The sides and rear walls of the baler are preferably braced by angle bars 1^c as shown, to stiffen them.

The base frame 1 preferably projects beyond the front wall of the chamber as 50 shown and may be provided with rollers 1^r, so that by tilting the baler forwardly its weight can be transferred to these rollers and it can then be easily moved from one position to another.

55 The baling chamber is open at top and its

front wall is preferably formed by a small upper door 2, and a larger door 3. The door 2 may be stiffened by a top piece 2^a and bottom angle bar 2^b; this plate and bar project beyond the ends of the door and are 60 adapted to be hingedly connected to a vertical rod 2^c which is fastened to the projecting ends of the adjacent angle braces 1^f on the sides of the baling chamber. The angle bar 2^b projects beyond the free end of the door and is adapted to engage a hook or catch 2^d which may be formed by upturning the end of the adjacent bar 1^f on the side of the baler as shown.

The lower door 3 may be braced by transverse pieces 3^x and is preferably hinged at its lower end to the frame by means of straps 3^e which engage a hinge rod 3^d passed through the side pieces of the base frame as shown. The vertical side edges of this 70 door are preferably reinforced by angle irons 3^a and the side flanges of these angle irons lap the side walls 1^b of the baling chamber when the door is closed and prevent spreading of the side walls when the 75 material is compressed in the chamber. The door 3 may be locked in closed position by means of latch rods 3^f, 3^g pivotally connected to a lever 3^h, at opposite sides of its pivot, said lever 3^h being pivoted at 3ⁱ on the 80 outer side of the door 3. The ends of these latch rods are adapted, when the door is closed, to engage perforations in keeper straps 3^j attached to the sides of the baling chamber and which project through slots 3^k 90 in the angle pieces 3^a when the door is closed, as shown in Fig. 1.

Adapted to operate within the baling chamber is a presser head, which preferably consists of a metal frame 4 to the 95 underside of which is attached a metal sheet 4^a. This presser head is suspended from an operating frame comprising a transverse bar or plate 5 and vertical angle bars 5^a which are rigidly connected to the plate 5 at 100 bottom and also rigidly connected together at top by a strap 5^c.

To the lower end of the bars 5 are connected rearwardly projecting plates 5^e, and the rear ends of these plates are bent and 105 perforated for the passage of rods 4^b which are connected to the front and rear bars of the presser head, and suspend the latter on the bars 5^a in such manner that the presser head can be moved upwardly or for- 110

wardly relatively to the plate 5, for a purpose hereinafter explained.

The angle bars 5^a are arranged side by side with parallel flanges extending rearwardly, and their front flanges extend transversely of the baler and are slidably engaged with guides 6, which may be formed of strap metal, rigidly attached to a supporting arch or bar 6^a extending transversely of and above the baling chamber and supported upon metal plates 6^b attached to the upper ends of the side walls 1^b of the baling chamber and projecting above the same as shown.

15 The guides 6 may be stiffened and held rigidly in position by means of inclined braces 6^c, 6^d attached to the guides and to the plates 6^b as indicated in the drawings.

The front flanges of the actuating bars 5^a are perforated, as at 5ⁿ, for the engagement of pawls 7 which are pivotally attached to an actuating lever 7^b (at opposite sides of the pivot of said lever) which is pivoted on a bolt 7^c attached to the arch bar 6^a intermediate the bars 5^a. Preferably an auxiliary arch bar 6ⁿ is arranged beside and in front of the bar 6 to support the pivot 7^c and assist in guiding the lever 7^b and the dogs 7 in their movements.

30 Each dog 7 can be tilted on its pivot so that its tooth 7^a can engage the notches or perforations 5ⁿ in the presser actuating bars 5^a when the dog descends. When the dog rises its tooth will ride out of the notch.

35 The dogs are pressed inward by means of springs 7^e so that each dog will engage its related presser-actuating bar 5^a when said dog descends. It will be seen that when the lever 7 is moved up or down one of the dogs will be raised and the other will be lowered, so that they will work in alternation, and therefore by oscillating lever 7^b the presser head can be rapidly lowered and the material in the baling chamber can be compressed according to the amount of leverage or force applied to the lever 7^b. The dogs 7 may be guided in their vertical movements by means of slotted plates 6ⁿ attached to the guides or braces above the dogs as shown in Figs. 1 and 2.

40 The lever 7^b may be operated from the side of the press; or it may be connected by a rod 7^m to a lever 7ⁿ pivoted at 7° on one side of the baling chamber, which lever 7ⁿ can be readily operated by a person standing in front of the baler; and it may be guided in its movements between a rod 7^p and strap 7^q on the side of the baling chamber, as shown in Fig. 1.

45 When it is desired to raise the baler head the dogs 7 must be disengaged from bars 5^a; and for this purpose I have shown them as loosely connected by a chain 7^r; and by pulling on such chain both dogs can be disengaged from the bars 5^a and the presser head

raised. In order to raise the presser head automatically I prefer to employ a spring 8, the lower end of which may be fastened to a plate 5^x secured between the plates 5^e, and the upper end of this spring is attached to a bracket or plates 6^b secured to the upper ends of the guides 6 as shown. The spring is of such strength that it will normally raise the presser actuating bars and the presser head suspended thereon to the highest position when the dogs are disengaged from the bars 5^a; said spring being put under tension as the presser head is lowered. To prevent the sudden lifting of the presser head by contraction of the spring 8 a brake 80 may be provided as shown in Figs. 5 and 6 comprising a shoe 6ⁿ adapted to engage the flange of one of the bars 5^a, and adjustably pressed thereagainst by means of a screw 6° which may be provided with a lock nut 6^p. 85 This bolt can be adjusted so as to bind the flange of the presser bar 5^a between the shoe and the arch bar 6^a with sufficient frictional resistance to prevent too sudden or snap action of the spring 8 in raising the presser head.

The presser head is preferably provided with three corrugations or grooves indicated at 4^c, and the front and rear bars of the frame 4 are notched as at 4^d adjacent the ends of these corrugations, to enable the ties or wires W (which are used to fasten a bale when compressed) to be adjusted and to have any slack taken up while the bale is under compression.

50 For the purpose of holding the bale ties W in position during compression of a bale, I preferably provide at the top of the baling chamber and on the rear wall thereof a wire holding device comprising a metal strip 9 provided with notched flanges 9^a, with which the ties W are engaged. Adjacent each notch and attached to the plate 9 is a spring plate 9^c which retains the ties in engagement with the notches when inserted therein, the ties are slipped under these springs and into the notches in the flanges. A similar tie holder is secured in the bottom of the chamber adjacent the rear wall thereof; as indicated in Fig. 2. In 115 the front door 3 and near the lower edge thereof are perforations 3ⁿ through which the other ends of the ties can project during the baling operation.

55 Operation: When the baler is to be used, 120 the ties W are engaged with the notched retainers 9 at the top and bottom of the chamber and the lower ends of the ties may be inserted through the openings 3ⁿ in the door 3 and the latter closed. The upper end of the wires can be caught over the front edge of the presser head which is then raised to its highest position and can be pressed backward partially out of the chamber as indicated in dotted lines in Fig. 125 130

3. The door 2 can remain open until the baling chamber is completely filled; then it is closed and the presser head pulled forward to the position shown in full lines 5 in Fig. 3. Then by operating the lever 7^b bars 5^a are forced downward, and the presser head lowered, forcibly compressing the material in the baling chamber. When the material is sufficiently compressed the 10 doors 2 and 3 may be opened and the ties can be readily adjusted under the head through the grooves 4^e and all slack taken up and the ties united thus securely tying the bale; then the dogs 7 are released by 15 pulling on the chain 7^f whereupon the spring 8 immediately lifts the presser-head and presser actuating bars to the position shown in Fig. 1, and the bale can be removed, the springs 8^c yielding sufficiently 20 to permit the disengagement of the ties from the notches when the bale is tilted out of the chamber.

What I claim is:

1. In combination, a baling chamber, a 25 presser-head therein, perforated pull bars connected with said presser-head, an oscillating lever, dogs connected with said lever at opposite sides of its pivot and adapted to alternately engage the perforations in the related bars and depress said head when the lever is oscillated; springs for holding the dogs yieldingly in engagement with the perforated pull bars, means for raising the presser-head, and means for 30 moving the dogs away from said bars to permit the presser-head to rise.

2. In a baler, the combination of a baling chamber, a presser-head therein, a pair of presser bars connected therewith, a pair of 40 pull dogs each adapted to engage one of the said bars, a lever for reciprocating said dogs simultaneously in opposite directions; means for normally holding the dogs in yielding engagement with the bars, a spring for 45 raising the presser-head, and means for guiding the dogs as they are reciprocated, and means for moving the dogs away from said bars and holding same out of engagement therewith to permit the presser-head 50 to rise.

3. In combination, a baling chamber, a presser-head therein, a presser-bar connected therewith having a perforated flange, a dog adapted to engage the perforations in the 55 flange, an oscillating lever for reciprocating said dog, means for yieldingly pressing the dog toward said bar and a guide for said dog; with a spring for raising said bar and presser-head, and means for disengaging the 60 dog from said bar to permit the presser-plate to rise.

4. In combination, a baling chamber, a presser-head therein, a pair of presser-bars connected therewith, means for guiding said 65 bars, a pair of pull dogs each adapted to en-

gage the adjacent bar, and an oscillating lever for actuating said dogs simultaneously in opposite directions; with means for guiding said pull dogs, springs for yieldingly pressing the dogs toward said bars, means for automatically raising the presser-head, 70 means for disengaging the dogs from said bars to permit the presser-head to rise, and means for controlling the ascent of the head.

5. In combination, a baling chamber, a 75 presser-head therein, a pair of presser-bars connected therewith and extending out of the chamber, means for guiding said bars, a pair of pull dogs each adapted to engage one of the bars, an oscillating lever connected with said pull dogs for reciprocating them simultaneously in opposite directions; springs for yieldingly pressing the dogs toward said bars, a spring for raising said bars, means for disengaging the dogs from 80 said bars to permit the presser-plate to rise, and means to retard the ascent of the presser-plate when being raised by the spring.

6. In a baler, the combination of a baling chamber, a pair of vertically movable 90 presser-bars connected therewith and extending out of said chamber, and means for operating said bars; with a presser-head slidably connected with and suspended from the lower ends of said bars and adapted to be 95 slid backward thereon out of the way when the presser-head is raised to the top of the chamber, substantially as described.

7. In combination, a baling chamber having a front door provided with openings for 100 the passage of the ties, notched plates for detachably securing the ties adjacent the rear lower part of the chamber, and adjacent the rear upper part of the baling chamber for retaining the ties in position during the 105 baling operation.

8. In combination, a baling chamber having a front door provided with openings for the passage of bale ties, a notched plate for detachably engaging the ties at the rear 110 lower part of the baling chamber, and a similar notched plate near the upper rear part of the chamber for retaining the ties during the baling operation; with a vertically movable presser-head notched on its 115 under side to permit the passage of the ties thereunder, and means for operating said baler-head, substantially as described.

9. In a baler, the combination of a baling chamber, a presser-head therein, and means 120 to depress said head; with means for automatically raising the presser-head, and means for retarding the speed of the head as it rises.

10. In a baler, the combination of a baling 125 chamber, a presser-head therein, bars connected with said presser-head, and means to engage said bars and cause the head to compress the material; with means for automatically returning the presser-head, and means 130

engaging the bars for retarding the speed of the head as it returns.

11. A baling chamber comprising a base, and side and rear walls attached to the base, 5 a pair of doors for closing the front of the chamber, the lower door having angle irons at its sides adapted to lap the front edges of the sides of the chamber and prevent lateral spreading thereof when the door is closed, 10 and means for securing the doors in closed position.

12. In combination, a baling chamber, a presser-head therein, a pair of parallel perforated presser-bars connected therewith and 15 extending out of the chamber, guides for the presser-bars, a pair of oppositely movable dogs respectively adapted to engage the perforations in the related one of the presser-bars, means for reciprocating the dogs simultaneously in opposite directions, and means for yieldingly pressing the dogs toward said bars so as to cause the descending dog to engage with its related bar, substantially as described.

25 13. In a baler, the combination of a baling chamber, a presser-head therein, presser actuating bars connected with said presser-head, guides for said presser bars, movable pull dogs adapted to alternately engage and 30 depress said bars, means for simultaneously moving the dogs in opposite directions, means for guiding the dogs as they are reciprocated, and springs for holding the dogs yieldingly in engagement with the related bars.

35 14. In combination, a chamber, a presser-

head therein, a pair of parallel perforated presser-bars connected therewith, means for guiding said bars, a pair of toothed pull dogs beside the said presser-bars, each pull dog 40 being adapted to engage the adjacent bar when the dog descends, means for reciprocating said pull dog simultaneously in opposite directions, means for guiding the dogs as they are reciprocated, and means for 45 yieldingly pressing the dogs toward said bars to cause their engagement therewith when they descend, and to permit them to ride thereover when they ascend.

15. A baling chamber comprising front, 50 side and rear walls and base, a pair of doors for closing the front of the chamber; a presser-head in said chamber, a pair of parallel vertical presser-bars connected therewith having perforated flanges, dogs having 55 teeth adapted to engage the perforations in the flanges of the related bars, an oscillating lever connected with said dogs for reciprocating them simultaneously in opposite directions, and means for yieldingly pressing 60 the dogs toward said bars so as to cause the teeth of the descending dog to engage and operate the related bar, substantially as described.

In testimony that I claim the foregoing as 65 my own, I affix my signature in presence of two witnesses.

LYNN W. MACOMBER.
